SEWING MACHINE

Hans Hacklander, Linden, N. J., assignor to The Singer Manufacturing Company, Elizabeth, N. J., a corporation of New Jersey

Application July 9, 1945, Serial No. 603,926

24 Claims. (Cl. 112—16)

1

This invention relates to sewing machines and more particularly to sewing machines of the type having feeding wheels for feeding the work to and past the stitching mechanism.

A principal object of the present invention is to provide an improved simplified mechanism for actuating both the feeding and stitch-forming devices so as to improve the high speed operation of this type of sewing machine.

A further object of the invention is to provide the present type of sewing machine with actuating mechanism which will be most simple in its construction and which will require the minimum cost to manufacture and install.

Another object of the invention is to provide a sewing machine of the present type with actuating mechanism characterized by its vibration-free operation.

The invention has for a further object to provide a cup-feed sewing machine that is adapted to have its driving pulley located beneath the level of the work table upon which the machine is mounted.

The invention, both in structure and in operation, as well as additional objects thereof, will be best understood from the following description taken in conjunction with the accompanying drawings, in which:

Fig. 1 is a front elevation of a sewing machine embodying the invention.

Fig. 2 is a left side elevation with a portion of the machine-frame broken away to show the adjustable mounting of the uncurling device.

Fig. 3 is a vertical transverse sectional rear view taken through the machine-frame, substantially along line 3—3 of Fig. 2, and illustrating the main-shaft and some of the connections actuated thereby.

Fig. 4 is a vertical longitudinal sectional view taken through the machine-frame substantially along line 4—4 of Fig. 1, and illustrating the needle-bar, and needle-thread looper mechanisms.

Fig. 5 represents the lower portion of a vertical longitudinal sectional view taken through the machine-frame, substantially along line 4—4 of Fig. 1, and illustrating a modified form of main-shaft drive.

Fig. 6 is a horizontal sectional view taken through the machine-frame, substantially along line 6—6 of Fig. 1, and illustrating the angular arrangement of the supporting members for the looper and spreader elements.

Frame and general structure

Referring in detail to the drawings, the present illustrated embodiment of the invention includes the machine-frame 1 having a base-portion or standard 2 and a laterally projecting overhanging bracket 3. Formed integral with

the base-portion 1 and disposed beneath the overhanging bracket 3 is an extension 4 and a supporting lug 5, the latter sustaining the inner feed-cup 6. Cooperating with the inner feed-cup 6 is an outer feed-cup 7 which depends from the overhanging bracket 3. Removably secured upon the bracket 3 is a cover-plate 8 which is secured to the bracket 3 by means of a screw 9.

Adjacent the top of the base-portion 1 is a horizontal partition 10 which divides the machine-frame into a lubrication compartment 11 and a belt compartment 12, see Fig. 4. The lubrication compartment 11 is closed at the bottom by means of a plate 13 secured by screws 14 and sealed by a gasket 15. As shown in Fig. 5, the machine is adapted to rest upon resilient pads P, of rubber, felt or the like, interposed between the plate 13 and the top of a table T. This resilient mounting for the machine absorbs vibrations which would otherwise be transmitted to the table.

Disposed vertically in the lubrication compartment 11 longitudinally of the arm-standard 2 is a main-shaft 16 journaled in bushings 17 and 18 as well as in lug 19 of plate 13. The bushing 17 is secured in the top portion of the partition 10 by means of screws 20, and the bushing 18 is supported in a lug 21 which projects inwardly from the wall of the machine standard 2. Mounted on the top portion of the main-shaft 16 is a balance or hand-wheel 22 which is secured to the shaft by means of a set screw 23.

The lower portion of the main-shaft 16 projects into the lug 19 provided with an oil chamber 24 which is closed by means of a plate 25 and gasket 26. The chamber 24 forms in its lower portion a sump which is adapted to contain oil whose normal level is shown by a line L in Fig. 4. This oil will find its way into conduit 27 which is provided in plate 13 and which leads to the chamber 24. A spiral groove 28 provided on the lower portion of the main-shaft 16 will, when the shaft is properly rotated, force the oil from the chamber 24 into the radial hole 29 by way of the annular groove 30 which is also provided in the main-shaft. The radial hole 29 communicates with a longitudinal bore 31 which will permit the oil to be delivered upwardly through the main-shaft and its associated cranks until it reaches a second radial hole 32 from which the oil will debouch into an annular chamber 33 provided in the bushing 17. As may be best seen from Fig. 4, the bushing 17 is provided with an oil passageway 34 and an associated conduit 35 which deliver the oil from the chamber 33 to a horizontally disposed drip-pan 36 carried in the upper portion of chamber 11.

To prevent leakage of oil at the upper portion of the main-shaft, the flanged bushing 17 is provided with an undercut circular recess 37 en-

tered by the lower hub-portion 38 of the balance-wheel 22. Formed in the portion 38 of the balance-wheel 22 are two circular oil-collecting undercuts 39. In the event that some oil should be forced upwardly along the main-shaft from chamber 33 it would be collected in the undercut 39 and thrown off by centrifugal force into the recess 37. The machine may be properly filled with oil through the threaded port 40 which is closed by a threaded plug 41.

The main-shaft 16 is driven by a belt 42 through the medium of a grooved pulley 43 secured by means of a set screw 44 to a horizontally disposed stub-shaft 45 which is journaled in a bushing 46. This bushing 46 is mounted in an apertured lug 47 which projects inwardly from the side wall of the standard 2. Secured by a set screw 48 to the stub-shaft 45 is a bevel-gear 49 which meshes with a similar gear 50 secured to the shaft 16 by a set screw 51. Thus the belt 42 may impart rotary motion to the main-shaft 16.

The stub-shaft 45 is lubricated by oil which runs down the outside of the main-shaft 16 and collects in a catch-pan 52 surrounding the shaft and secured to the lug 21 by a screw 53. This catch-pan 52 has a downturned lip portion 54 which is positioned directly over a cavity 55 provided in the lug 47 for the purpose of delivering oil to a radial hole 56 formed in the bushing 46. Oil passing through the hole 56 is fed along the stub-shaft by means of a spiral groove 57, thereby to lubricate the shaft bearing.

As may be best seen from Fig. 3, the pulley 43 and belt 42 are enclosed by means of a housing-cap 58 secured to the standard 2 by means of a screw 59 which projects through a housing lug 60 and is threaded into the side wall of the standard 2.

A modified form of main-shaft driving means is disclosed in Fig. 5. Here the lower portion of shaft 16 extends into a flanged bearing-element 61 which is secured to the plate 13 by means of screws 63. In this modification, the plate 13 is provided with a bearing-receiving aperture 64 and a gasket 65 is placed between the plate 13 and the flange of the bearing 61. A grooved pulley 43' is secured to the lower portion of the shaft 16 by means of a screw 44'.

In order to prevent the oil from leaking out of the chamber 11 along the shaft 16, there is provided in the bearing element 61 a chamber 66 which is filled with packing 67. A packing plug 68 is threaded into the lower portion of the chamber 66 for the purpose of exerting upward pressure upon the packing 66, thereby to provide an oil-impervious seal.

This modified drive obviates the use of the hereinabove described stub-shaft 45 and its associated gears 49 and 50. Furthermore, as best seen in Fig. 5, this construction permits the machine to be mounted upon the usual power-table in a manner such that the driving element, including the pulley 43' and the belt 42, are completely disposed beneath the level of the table-top T.

Located in the belt compartment 12, see Fig. 4, is a conventional clip-belt 69 for driving the outer feed-cup 7. Also located in the compartment 12 is a pivotally mounted supporting lever 70 for the outer feed-cup 7. A lighting attachment 71 is disposed in the partition 10. The belt compartment 12 is not opened to the lubrication compartment 11, so that the oil-laden atmosphere in the latter compartment does not find its way

onto the stitch-forming instrumentalities or the feed-cups, or soil the work.

From the above description, it will be understood that there is provided a machine-frame divided into two compartments, one of which is oil-tight and houses actuating mechanism operating at a high rate of speed, while the other of which is opened to the atmosphere and houses some of the slow speed mechanism.

Needle-bar mechanism

Referring to Figs. 4 and 6, it will be observed that the needle-bar mechanism comprises a needle 72 fixed in a needle-clamp 73 secured upon a horizontally disposed reciprocatory needle-bar 74 journaled in a bushing 75 fixed in the machine-frame. The inner end portion of the needle-bar 74 has secured thereon a collar 76 containing a vertically disposed cross-pin 77 which is pivotally embraced by the forked end 78 of a pitman rod 79. The end portion 80 of the pitman rod 79 embraces a crank portion 81 of the shaft 16. As may be seen in Fig. 6 the needle-bar 74 and the shaft 16 have their respective longitudinal axes disposed in a single vertical plane.

From the above, it will be obvious that rotation of the main-shaft 16 imparts to the needle-bar 74, through the connections just described, a reciprocatory motion in time with the other stitch-forming instrumentalities later to be described.

A thrust collar 82 is secured upon the main-shaft 16 by means of a set screw 83 for the purpose of cooperating with a flange 84 of the crank 81 in preventing any endwise movement of the shaft 16. The flange 84 and the collar 82 are each adapted to bear against an opposite end portion of the bushing 18.

Looper mechanism

Referring particularly to Figs. 3, 4 and 6, a looper 85, which is of the threaded type, is timed so that it enters the thread-loop presented by the needle 72 during the beginning of the needle-return or withdrawal stroke, thereby carrying into the needle-thread loop a loop of thread passing through an eye of the looper.

The looper 85 is secured in a clamp 86 fastened upon the outer end of a horizontally disposed supporting shaft 87 journaled for oscillation in an angularly disposed elongated bushing 88 fixed in the machine-frame above the level of the needle-bar 74. Clamped upon the inner end of the looper-shaft 87 is one end of a rock-lever 89 having at its other end a ball 90 and an extended guide-pin 91, the ball 90 being embraced by the socketed end of a pitman 92 formed at its other end with a split strap 93 adapted to embrace a ball-crank 94 fastened upon the main-shaft 16. To prevent the pitman 92 from turning, there is secured to one end portion thereof a forked member 95 which straddles the pin 91 on the rock-lever 89.

The function of the looper 85, as indicated briefly above, is first, to seize the thread-loop presented by the needle 72, thereby enchaining the needle and looper threads, and secondly, to position that portion of thread carried by the looper and adjacent the looper-eye 96 so that the looper-thread can be engaged by a spreader which presents the looper-thread-loop to the needle for entrance by the latter. In the machine disclosed, these two steps are effectively carried out by a simple oscillation of the looper 85 about the longitudinal axis of the supporting

or rock-shaft 81. In order that the movement of the looper 85 may be reduced to a minimum, the longitudinal axis of the supporting shaft 81, see Fig. 6, is angularly arranged at an acute angle with respect to a vertical plane passing through the axis of the needle-bar 74. It will be understood that the looper point moves in a single plane and that only oscillatory movements need be imparted to the looper.

Referring to Fig. 4, it will be observed that the longitudinal axis of the looper-supporting shaft 81 is disposed in a substantially horizontal plane.

Spreader mechanism

Cooperating with the looper 85 and operating to spread the thread-loop presented by the looper for entrance by the needle 72 prior to its penetration of the fabric is a spreader 91, see Fig. 6. The spreader 91 is forked at its free end and is secured in a clamp 98 fastened upon the outer end of a horizontally disposed supporting shaft 99 journaled in an elongated bushing 100 fixed in the machine-frame above the level of the needle-bar 74 and below the level of the looper-shaft 81. Clamped upon the inner end of the supporting shaft 99 is a rock-bar 101 formed at its other end with a ball 102 and an extended pin 103. The ball 102 is embraced by the socketed end of a pitman 104 whose other end is formed with a two-part strap 105 embracing a ball-crank 106 fast upon the main-shaft 16. To steady the pitman 104, there is secured to the upper end-portion thereof a forked member 107, which straddles the pin 103 on the rock-lever 101. The longitudinal axis of the spreader-shaft 99 lies in a vertical plane inclined to the vertical plane containing the longitudinal axis of the needle-bar 74.

The function of the spreader 91 is to distend the looper-thread-loop so that the needle 72 will enter the same immediately before it penetrates the fabric. In view of the angular arrangement of the spreader-supporting shaft 99, see Fig. 6, the motion required of the spreader is only an oscillatory motion of relatively small arc about the longitudinal axis of the supporting shaft 99. It will be seen that the spreader point also moves only in a single plane.

The angular or convergent arrangement of the looper-supporting shaft 81 and the spreader-supporting shaft 99 is of decided utility in that the only motions required of the looper 85 and the spreader 91 are oscillatory movements. Preferably the needle-bar 74, looper-supporting shaft 81 and spreader-supporting shaft 99 all have their longitudinal axes disposed in parallel planes (see Figs. 3 and 4), which in the machine illustrated are horizontal. It will be noted that the actuating pitmans 79, 92 and 104 also have their respective longitudinal axes normally disposed in planes parallel to each other as well as parallel to those planes containing the above noted looper, spreader and needle elements.

By thus disposing these elements in parallelism with each other and at right angles to the shaft 16, the machine, as a unit, lends itself to simple assembly methods and at the same time requires only the simplest mechanical movements to actuate the cooperating elements. Thus the cost of the machine may be held at a minimum, and wear and vibration are reduced to a minimum.

From Fig. 3 it may be noted that the cranks 84, 94 and 106 are each lubricated by means of a radial aperture leading from the main shaft bore 31 to the crank periphery. Respectively, these

radial apertures are numbered 108, 109 and 110. Furthermore, the drip-pan 36 is provided with depending conduits 111 and 112 for carrying oil to the balls 102 and 90, respectively.

The hereinabove described looper 85, spreader 91 and needle 72 elements all are disposed relative to each other and operate together in a manner described and disclosed in my U. S. Patent No. 2,277,971, issued March 31, 1942.

10 Feeding mechanism

The work is adapted to be fed intermittently through the machine, in one form of the machine, in a vertically disposed position by means of the inner feed-cup 6 and the outer feed-cup 7. Referring particularly to Figs. 3 and 4, it will be seen that the inner feed-cup 6 is secured by a screw 113 upon the upper reduced end-portion of a vertical feed-shaft 114 which is journaled in spaced bushings 115 and 116 fixed in the frame-lug 5 and the extension 4, respectively. Forming a housing for the vertical feed-shaft 114 is a relatively thin stationary tube 117 of which the upper end is fixed in the lug 5 and the lower end is fixed in the extension 4.

The feed-shaft 114 has fastened upon its lower end-portion a spur gear 118 which meshes with a second spur gear 119 secured to the lower end of the feed-actuating shaft 120 journaled within the compartment 11. The feed actuating shaft 120 is intermittently turned by a common form of one-way clutch 121 having an actuating-arm 122 connected by a pitman 123 to an adjustable feed-eccentric 124. Access to the adjustable eccentric 124 may be had by removing the plug 41 in the machine-frame. The provision of the adjustable eccentric permits the amount of turning movement imparted to the feed-cups 6 and 7 to be varied in accordance with the stitch-length desired.

Referring now to Fig. 4, the feed-actuating shaft 120 has secured upon its upper end a peripherally grooved belt-pulley 125 which is connected by a common form of clip-belt 69 to a second or outer, notched belt-pulley 126 fastened upon the upper end of a depending feed-shaft 127 supporting at its lower end the outer feed-cup 7. The depending feed-shaft 127 is journaled in spaced bearings provided in the opposite ends of a pivotally sustained sheath 128 in the usual fashion. The upper end of the sheath 128 is clamped by a screw 129 in the split end 130 of the pivotally mounted feed-cup supporting lever 70. From the above description, it will be understood that the two feed-cups 6 and 7 are intermittently driven simultaneously to advance the material in one direction past the stitching mechanism, and that the amount of movement imparted to the feed-cups for reciprocation of the needle is controlled by the adjustable feed eccentric 124.

For a more detailed description of the present cup-feeding mechanism along with its accompanying one-way clutch 121 and adjustable eccentric 124, reference may be had to my U. S. Patent No. 2,277,971, issued March 31, 1942.

65 Feed-cup separating mechanism

To facilitate the introduction of the work between the two feed-cups 6 and 7, means is provided whereby the outer feed-cup 7 can be shifted away from the inner feed-cup 6 whenever desirable. This means comprises the feed-cup supporting lever 70 which, as previously described, has clamped in its split forward end 130 the sheath 128 in which is journaled the feed-

shaft 121. This lever 70 is pivotally mounted upon a pin 131 carried by a bracket 132 which in turn is carried by the machine-frame.

At the inner end of the feed-cup supporting lever 70 there is formed a stop-arm 133 adapted to be received between two adjustable stop-bars 134 and 135, which limit the extent of movement of the outer feed-cup 7 toward and away from the inner feed-cup 6. The screws 136 and 137 are adapted for adjusting the stop-bars 134 and 135. A control rod 138 connected at its lower end to a foot-treadle (not herein shown) and at its upper end to the lever 70 is provided for swinging the outer feed-cup 7. The control-rod 138 extends through a sheath 139 enclosed by a housing 140 which at its lower end is pressed into an aperture provided in an upstanding boss 141 integral with the bottom plate 13. A spring, not herein shown, is provided for maintaining the outer feed-cup 7 in its lowered or operative position. For a more complete disclosure and description of this feed-cup separating means, reference may be had to my above noted prior patent.

Miscellaneous devices

The present machine is fitted with a lighting means adapted to direct a light to the area of the stitching point so that the operator may observe the character of the stitching and the position of the work as it passes through the machine. This lighting means comprises a light bulb 142 carried in a socket 143 which is mounted in an inclined cavity formed in the machine-frame wall.

Current is supplied to the lamp from a suitable source by an insulated conductor 144 which extends through a tubular conduit 145 passing vertically through compartment 11. For a more detailed description of the present lighting attachment reference may be had to my prior U. S. Patent No. 2,277,972, March 31, 1942.

When the machine illustrated is used for certain operations, such as seaming hosiery, it is fitted with an uncurling guide 146 which uncurls and directs the edges of the fabric preparatory to stitching. The uncurling guide 146 is mounted upon a bracket 147 which is secured to the machine-frame by means of a screw 148. For a more detailed description of the present type of uncurling guide reference may be had to U. S. Patent No. 2,256,881 issued Sept. 23, 1941.

From the foregoing description considered in connection with the accompanying drawings, it will be clear that the present machine is a marked improvement over the prior art devices in that its actuating elements are characterized by their utmost simplicity both in construction and in arrangement. For example, by referring to Fig. 4 it may be seen that the driving mechanism comprises merely a main-shaft 16 from which looper, spreader, needle and feeding elements are directly driven. No complicated ancillary mechanisms are required for connecting these above elements with the main-shaft. The only connecting mechanisms herein used are four simple pitman rods, all of which are disposed in parallel relation with each other and at right angles to the driving shaft 16. Thus, these actuating elements, being of simple design, are not only inexpensive to manufacture, but they are readily assembled within the machine-frame. Furthermore, since the above noted four pitman rods are all confined to operate in parallel planes at right angles to the drive-shaft, the problem of prop-

erly balancing the driving elements is simplified and thus a superior smooth running machine is produced.

Having thus set forth the nature of the invention, what I claim herein is:

- 5 1. A cup-feed sewing machine having a frame including a hollow standard, a rotary actuating shaft disposed within and extending longitudinally of said standard, an endwise reciprocatory needle-bar journaled in said standard with its longitudinal axis normal to and disposed in a plane containing the longitudinal axis of said rotary actuating shaft, a needle carried by said needle-bar, rock-shafts respectively disposed at opposite sides of and at acute angles with respect to said needle-bar, means operatively connected to said actuating shaft for driving said rock-shafts, thread-handling implements carried by said rock-shafts for cooperation with said needle in the formation of stitches, opposed rotary feed-cups disposed externally of said standard with their rotation axes substantially parallel to said rotary actuating shaft, and means operatively connected to said actuating shaft for driving said feed-cups.
- 10 2. A sewing machine having, in combination, a frame provided with a wall, feed-cups located exteriorly of and supported by said frame adjacent said wall, a reciprocatory needle and two oscillatable loop-handling implements, a reciprocatory needle-carrying bar, a pair of rock-shafts for carrying said loop-handling implements, said needle-carrying bar and said rock-shafts being mounted in the frame so as to project through said wall, a rotary actuating shaft carried by said frame with its longitudinal axis disposed in parallel relation with the axis of rotation of one of said feed-cups and at right angles to and in a plane containing the path of movement of said needle, and means operatively connecting said needle-carrying bar and said rock-shafts with said rotary actuating shaft.
- 15 3. A sewing machine having, in combination, a frame provided with a wall, feed-cups located exteriorly of and supported by said frame adjacent said wall, a reciprocatory needle and two oscillatable loop-handling implements for cooperating with said needle in the formation of stitches, a reciprocatory needle-carrying bar journaled in said wall with the longitudinal axis thereof disposed at right angles to the axis of rotation of one of said feed-cups, a pair of rock-shafts for carrying said loop-handling implements, a rotary actuating shaft journaled within said frame and disposed in parallelism with the axis of rotation of one of said feed-cups, a pair of pitman rods each operatively connecting said rotary actuating shaft with a respective one of said rock-shafts, said pitman rods each being disposed substantially at right angles to said rotary actuating shaft, and means operatively connecting said needle-carrying bar with said rotary actuating shaft.
- 20 4. A sewing machine having, in combination, a frame provided with a wall, feed-cups located exteriorly of and supported by said frame adjacent said wall, a reciprocatory needle and two cooperating oscillatable loop-handling implements, a reciprocatory needle-carrying bar, a pair of rock-shafts for carrying said loop-handling implements, said needle-carrying bar and said rock-shafts being mounted in the frame with the longitudinal axes of said three elements lying in planes parallel to each other, a rotary actuating shaft carried by said frame and disposed at right angles to said parallel planes and in a plane containing

- 70
- 75

the axis of rotation of one of said feed-cups, and means operatively connecting said needle-carrying bar and said rock-shafts with said rotary actuating shaft.

5. A sewing machine having, in combination, a frame provided with a wall, a pair of opposed feed-cups disposed at one side of said wall and supported by said frame, a rotary actuating shaft carried by said frame and disposed at the other side of said wall with the longitudinal axis thereof in parallelism with the axes of rotation of said feed-cups, a reciprocatory needle-carrying bar, a pair of loop-handling implements, a pair of rock-shafts for carrying said loop-handling implements, said needle-carrying bar and said rock-shafts being carried by said wall, and means operatively connecting said rotary actuating shaft with said needle-carrying bar and said rock-shafts.

6. A sewing machine having, in combination, a frame provided with a wall, a pair of opposed feed-cups disposed at one side of said wall and supported by said frame, a rotary actuating shaft carried by said frame and disposed at the other side of said wall with the longitudinal axis of said shaft in parallelism with the axes of rotation of said feed-cups, a reciprocatory needle-carrying bar movable in a plane containing the axis of one of said feed-cups, two oscillatable elements for producing stitches in cooperation with the needle, two rock-shafts for supporting said two oscillatable elements, each rock-shaft being disposed at an acute angle to a plane containing said needle-carrying bar and the axis of one of said feed-cups, and means operatively connecting said needle-carrying bar and said two rock-shafts to said rotary actuating shaft.

7. A sewing machine having, in combination, a frame provided with a wall, a pair of opposed feed-cups disposed at one side of said wall and supported by said frame, a rotary actuating shaft journaled within said frame and having its longitudinal axis disposed in a plane containing and in parallelism to the axes of rotation of said pair of feed-cups, a reciprocatory needle-carrying bar projecting through said wall and having its longitudinal axis disposed within said plane and at right angles to the axis of rotation of one of said feed-cups, a pair of oscillatable loop-handlers, a pair of rock-shafts for supporting said two loop-handlers, each rock-shaft being disposed at an acute angle to said plane, and means operatively connecting said needle-carrying bar and said pair of rock-shafts to said rotary actuating shaft.

8. A sewing machine having, in combination, a frame provided with a wall, a pair of opposed feed-cups disposed at one side of said wall and supported by said frame, a rotary actuating shaft journaled within said frame and having its longitudinal axis disposed in parallelism with the axes of rotation of said feed-cups, a reciprocatory needle-carrying bar, a pair of oscillatable loop-handlers, a pair of rock-shafts for supporting said two loop-handlers, said needle-carrying bar and said rock-shafts each having its longitudinal axis disposed in a plane perpendicular to said rotary actuating shaft, and three pitman rods each operatively connecting said rotary actuating shaft with a respective one of said rock-shafts and said needle-carrying bar, the longitudinal axis of each of said pitman rods being disposed in a plane substantially perpendicular with said rotary actuating shaft.

9. In a sewing machine, a frame including a standard having a base and a laterally project-

ing overhanging bracket, a rotary actuating shaft vertically journaled within said standard, a pair of feed-shafts disposed in parallelism with said rotary actuating shaft with at least one of said feed-shafts depending from said overhanging bracket, a pair of opposed feed-cups carried by said feed-shafts exteriorly of said frame, means operatively connecting said feed-shafts to said rotary actuating shaft for rotation in one direction, a reciprocatory needle-carrying bar horizontally journaled in said standard, means operatively connecting said needle-carrying bar with said rotary actuating shaft, a pair of oscillatable loop-handlers, a pair of rock-shafts carried by said standard for supporting said loop-handlers, and a pair of substantially horizontally disposed pitman rods each operatively connecting said rotary actuating shaft with a respective one of said rock-shafts.

10. In a sewing machine, a frame including a standard having a base and a laterally projecting overhanging bracket, a rotary actuating shaft vertically journaled within said standard, a pair of feed-shafts disposed in parallelism with said rotary actuating shaft with at least one of said feed-shafts depending from said overhanging bracket, a pair of opposed feed-cups carried by said feed-shafts exteriorly of said frame, means operatively connecting said feed-shafts to said rotary actuating shaft for rotation in one direction, a reciprocatory needle-carrying bar horizontally journaled in said standard, means operatively connecting said needle-carrying bar with said rotary actuating shaft, two oscillatable thread-handling implements, supporting means for said oscillatable thread-handling implements including rock-shafts journaled in said standard, said rock-shafts being relatively convergent toward the implements carried thereby, and means including a pair of pitman rods for connecting said rock-shafts to said rotary actuating shaft for imparting operative movements thereto.

11. A sewing machine having a base, a standard supported upon said base, a rotary actuating shaft vertically journaled within said standard with the lower end portion thereof extending through and below said base, a belt-pulley mounted upon the extended lower end portion of said rotary actuating shaft, a pair of opposed feed-cups carried by said standard, means operatively connecting said feed-cups with said rotary actuating shaft, a reciprocatory needle and a pair of oscillatable loop-handling instrumentalities for cooperation with said needle in the formation of stitches, and means connecting said needle and said oscillatable loop-handling instrumentalities for operation from said rotary actuating shaft.

12. In combination, a table-top, a cup-feed sewing machine having a base mounted upon said table-top, a standard mounted upon said base, an actuating shaft journaled within said standard for rotation about an axis substantially normal to said table-top with one end-portion of said shaft extending through said base to the other side of said table-top, a belt-pulley secured upon the extended portion of said rotary actuating shaft, a pair of feed-shafts carried by said standard and disposed in parallelism with said rotary actuating shaft, a pair of opposed feed-cups carried by said feed-shafts, and means operated by said rotary actuating shaft for driving at least one of said feed-shafts.

13. In combination, a table-top, a sewing machine mounted upon and having a standard ris-

ing from said table-top, a rotary actuating shaft vertically journaled within said standard with the upper end portion extending through the top portion of said standard and the lower portion thereof extending below the level of said table-top, a hand-wheel mounted upon the upper extended portion of said rotary actuating shaft, a belt-pulley mounted upon the lower extended portion of said rotary actuating shaft, a pair of opposed feed-cups disposed above said table-top, stitching means including a substantially horizontally disposed reciprocatory needle and at least one loop-handling implement cooperating with said needle, and means operatively connected to said rotary actuating shaft for driving said feed-cups and for actuating said stitching means.

14. In a sewing machine, a frame including a standard having a base and a laterally projecting over-hanging hollow bracket, a rotary actuating shaft vertically journaled within said standard with the lower end portion thereof extending downwardly through said base and the upper end portion thereof extending upwardly through the top portion of said standard, a belt-pulley mounted upon the lower extended portion of said shaft, a hand-wheel mounted upon the upper extended portion of said shaft, a pair of feed-shafts disposed in parallelism with said main actuating shaft and having at least one of said shafts suspended from said hollow bracket, opposed feed-cups carried by said feed-shafts, a reciprocatory needle-carrying bar mounted in said standard, means operatively connecting said needle-carrying bar with said rotary actuating shaft, a pair of oscillatable loop-handlers for cooperation with the needle in the formation of stitches, a pair of rock-shafts for supporting and actuating said loop-handlers, and operative means connecting said rock-shafts with said rotary actuating shaft.

15. In a sewing machine, a frame including a standard having a base and a laterally projecting overhanging hollow bracket, a rotary actuating shaft vertically journaled within said standard with the upper end portion thereof extending through the top portion of said standard, a hand-wheel mounted upon the extended portion of said actuating shaft, a pair of feed-shafts disposed in parallelism with said actuating shaft and having at least one of said shafts suspended from said hollow bracket, opposed feed-cups carried by said feed-shafts, a reciprocatory needle-carrying bar mounted in said standard and operatively connected with said actuating shaft, a pair of oscillatable loop-handlers for cooperation with the needle in the formation of stitches, a pair of rock-shafts for supporting and actuating said loop-handlers, operative means connecting said rock-shafts with said actuating shaft, a driving-shaft journaled horizontally in said standard with one end portion thereof extending through said standard, a belt-pulley mounted upon the extended end portion of said driving-shaft, and means for operatively connecting said driving-shaft with said main actuating shaft.

16. A cup-feed sewing machine having, in combination, cooperating feed-cups between which the work passes, a frame provided with a closed lubrication compartment having a base portion removably secured thereto and forming an oil-containing sump, stitch-forming instrumentalities including a needle and at least two other thread-handling implements cooperating therewith, a rotary actuating shaft vertically journaled within said lubrication compartment with the

lower end portion thereof being provided with a spiral oil-pumping groove, and means carried by said base portion and cooperating with the grooved portion of said actuating shaft in the pumping of the oil from said sump to actuating mechanism within said frame.

17. A cup-feed sewing machine having, in combination, a frame, a pair of opposed rotary feed-cups carried by said frame for supporting and feeding fabric sections, driving means for rotating at least one of said feed-cups, stitch-forming instrumentalities including a reciprocatory needle and at least one complemental loop-handling element, a rotary actuating shaft journaled in said frame with its longitudinal axis disposed substantially parallel to the axes of rotation of said feed-cups, means operatively connecting said needle to said rotary actuating shaft, and means operatively connecting said loop-handling element to said rotary actuating shaft, said last named means including an operating shaft disposed at an angle to the plane containing the longitudinal axis of said rotary actuating shaft and the axis of rotation of one of said feed-cups.

18. A cup-feed sewing machine having, in combination, a frame, opposed rotary feed-cups carried by said frame for supporting and feeding fabric sections, driving means for rotating at least one of said feed-cups, stitch-forming instrumentalities including a reciprocatory needle and at least one complemental loop-handling element, a rotary actuating shaft carried by said frame with its longitudinal axis disposed substantially parallel to the axis of rotation of one of said feed-cups, means connecting said needle and said loop-handling element to said rotary actuating shaft for operation thereby, a driving shaft journaled in said standard for rotation about an axis transverse to the axis of said actuating shaft, and means connecting said driving shaft to said actuating shaft.

19. A cup-feed sewing machine having, in combination, a frame, opposed rotary feed-cups carried by said frame for supporting and feeding fabric sections, driving means for rotating at least one of said feed-cups, stitch-forming instrumentalities including a reciprocatory needle and at least one complemental loop-handling element, a rotary actuating shaft carried by said frame with its longitudinal axis disposed substantially parallel to the axis of rotation of one of said feed-cups, means connecting said needle and said loop-handling element to said rotary actuating shaft for operation thereby, a driving shaft journaled in said standard for rotation about an axis transverse to the axis of said actuating shaft with one end-portion thereof extending beyond said frame, means connecting said driving shaft to said actuating shaft, a belt-pulley fast on the extended end-portion of said driving shaft, and a cover-plate housing said belt-pulley and secured to said frame.

20. A cup-feed sewing machine having, in combination, cooperating rotary feed-cups between which the work passes, a frame provided with a closed lubrication compartment having a base portion forming an oil-containing sump, stitch-forming instrumentalities including a needle and at least one thread-handling implement cooperating therewith, a rotary actuating shaft vertically journaled within said frame with its lower end-portion extending into said lubrication compartment, said actuating shaft being provided with a longitudinal bore extending through the major portion of the length thereof, means car-

ried by said base portion and cooperating with the rotary actuating shaft for pumping oil from said sump through the bore of said rotary actuating shaft, operating elements connecting said stitch-forming instrumentalities and feed-cups to said actuating shaft for operation thereby, and means in communication with the bore in said rotary actuating shaft for conducting oil from the bore to said operating elements.

21. A cup-feed sewing machine having, in combination, a frame, opposed rotary feed-cups carried by said frame for supporting and feeding fabric sections, driving means for rotating at least one of said feed-cups, stitch-forming instrumentalities including a reciprocating needle and at least one complemental loop-handling element, a rotary actuating shaft carried by said frame with its longitudinal axis disposed in a plane containing the axis of rotation of one of said feed-cups, means operatively connecting said needle to said rotary actuating shaft, and means operatively connecting said loop-handling element to said rotary actuating shaft, said last named means including an operating shaft disposed above the level of said feed-cups with its longitudinal axis located at one side of the plane containing the longitudinal axis of said rotary actuating shaft and the axis of rotation of one of said feed-cups.

22. A cup-feed sewing machine having, in combination, a frame, opposed rotary feed-cups carried by said frame for supporting and feeding fabric sections, driving means for rotating at least one of said feed-cups, stitch-forming instrumentalities including a reciprocating needle and a plurality of complemental loop-handling elements, a rotary actuating shaft carried by said frame with its longitudinal axis disposed in a plane containing the axis of rotation of one of said feed-cups, means operatively connecting said needle to said rotary actuating shaft, and means operatively connecting said loop-handling elements to said rotary actuating shaft, said last named means including a carrier for each of said loop-handling elements located above the level of said feed-cups.

23. A cup-feed sewing machine having, in combination, a frame, opposed feed-cups rotatable about substantially parallel axes for supporting

and feeding fabric sections, driving means for rotating at least one of said feed-cups, stitch-forming instrumentalities including a reciprocating needle and at least one complemental loop-handling element, a rotary actuating shaft carried by said frame with its longitudinal axis disposed in a plane containing the axis of rotation of one of said feed-cups, means operatively connecting said needle to said rotary actuating shaft, and mechanism operatively connecting said loop-handling element to said rotary actuating shaft, said mechanism including a loop-handling element carrying shaft disposed above the level of said feed-cups and inclined relatively to the axis of rotation of at least one of said feed-cups.

24. A cup-feed sewing machine having, in combination, a frame, opposed feed-cups rotatable about substantially vertical axes for supporting and feeding fabric sections, driving means for rotating at least one of said feed-cups, stitch forming instrumentalities including a horizontally disposed reciprocating needle and at least one complemental loop-handling element, a needle-bar carrying said needle, a vertically disposed rotary actuating shaft carried by said frame, means operatively connecting said needle-bar to said rotary actuating shaft, and mechanism operatively connecting said loop-handling element to said rotary actuating shaft, said mechanism including a loop-handling element carrying shaft inclined relatively to the vertical axis of rotation of at least one of said feed-cups and relatively convergent with said needle-bar towards the needle carried thereby.
